Patented Mar. 15, 1921.

By FREDERIC P. GATES Inventor:

Johnnie Brown Attala

UNITED STATES PATENT OFFICE.

FREDERIC P. GATES, OF HARTFORD, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

1,371,782.

Specification of Letters Patent. Patented Mar. 15, 1921.

Application filed November 20, 1917. Serial No. 203,007.

To all whom it may concern:

Be it known that I, FREDERIC P. GATES, a citizen of the United States of America, residing at Hartford, in the county of Hartford and State of Connecticut, have invented certain new and useful Improvements in Electric Switches, of which the following is a specification.

My invention relates to electric switches and particularly to switches for electric lamp sockets, the object of my invention being to provide a switch mechanism of simple and economical construction, adapted to break relatively heavy current and susceptible of being installed within the limited confines of the insulating body of an ordinary lamp socket.

Referring to the accompanying drawings, Figure 1 is a plan view, partially broken away, of the insulating body of a lamp socket;

Fig. 2 is a vertical section therethrough on the line 2—2, Fig. 1;

Fig. 3 is a similar view on the line 3—3, Fig. 1;

Figs. 4, 5, and 6 are perspectives of details of the switch mechanism.

Referring to the drawings, the present socket comprises the usual socket casing and lining indicated in dotted lines 10, Fig. 1. Within the casing is supported the insulating body of the socket comprising inner and outer porcelain buttons 11 and 12, upon which the current carrying members of the socket are mounted. The binding terminals 13 and 14 for the lead wires are carried by straps 15 and 16, and wire grooves 17 and 18 lead to these terminals.

The strap 15, which carries binding screw 13, is angled over the base flange 19 of the screw shell terminal 20, mounted at the outer end of the socket body, and establishes direct electrical connection therewith. This strap is secured in position at one point by the screw bolt 21 passing through both buttons and thus serving to unite the latter together, as well as to hold the screw shell and strap in place. A second bolt 22 pierces only the outer button 12 and takes into the strap 15 at a point remote from the bolt 21.

The strap 16, leading from the terminal 14, is bent inward into the switch chamber between the buttons and forms the switch terminal 23. In order to hold this terminal

rigidly in position, its end is preferably extended into a hole 24, piercing the button 11. The other switch terminal 25 is formed by the angled end of the strap 26 passing down the outside of the button 12, and secured by a screw 27 to the base of the center contact 28. The screw shell 20 is apertured at 29 to permit the passage therethrough of the offset end of the strap 26 and the base of the terminal 28. The recess 30 in the button, in which the base of the terminal 28 is seated, is rectangular, thus holding the terminal in fixed position against any tendency to swivel. The inner end of the strap 26 is passed through hole 31 in button 11 to afford a secure anchorage similar to that afforded for the corresponding end of strap 16. It will be noted that these offset inner ends of the straps 16 and 26 are both clamped between the adjacent faces of the buttons 11 and 12 so that their extension into the holes 24 and 31 is not essential to their secure anchorage, although it adds rigidity.

The adjacent faces of the two buttons are recessed to afford a switch chamber 32. The portion of this chamber in the button 11 forms a bay 33 of substantially rectangular shape. Through the diagonally opposite corners of this bay pass the switch terminals 23 and 24. The switch contact serving to connect these terminals comprises a pair of conchoidal spring wings 34 and 35, carried by a metal drum 36 having, at one end, a ratchet plate 37, and at its other end, a bearing pin 38, journaled in a hole 39 in the button 11. A washer 40 may be interposed between the drum and the button to insure a smooth bearing. Coöperating with the ratchet plate 37 is a disk 41 having dogs 42 adapted to engage the arms of the ratchet plate 37. The plate 41 is mounted on an insulating carrier 43, which also carries the chain rail 44 for the pull chain 45. The carrier 43 and plate 41 are pierced in register at 46 to accommodate the spindle 47 passing therethrough, and entering the bore of the drum 36. Coiled upon the spindle 47 is a return spring 48, one end of which engages the tongue 49 of the plate 41, while its other end is passed through a hole in the squared head 50 of the spindle 47. The head 50 is seated in a correspondingly shaped well in the bottom of the recess 51, and thus normally holds the spindle against

rotation. In order to adjust the tension of the spring 48, the button 12 is pierced at 52 to permit the insertion of a screw driver into engagement with a slot in the head 50 of the spindle. By pushing the spindle 47 inward a sufficient distance to unseat the squared head 50 from its rectangular well, it may be rotated and the tension of the spring 48 increased or lessened, as may be desired.

10 The operation of the switch is readily understood. Upon pulling the actuating chain 45, the dogs 42 on the plate 41 engage the arms of the ratchet plate 37 and impart a rotary motion to the drum 36. This motion compresses the spring arms 34-35 against the contacts 23 and 24, and when the tension becomes sufficient to overcome the resistance offered by the frictional engagement of these parts, the spring arms 20 part from the terminal plates with a snap action and expand into a corresponding position a quarter turn in advance of that illustrated in Fig. 1. Upon the release of the pull chain 45, the plate 41 returns to its 25 original position, under the action of the return spring 48; but the spring contact arms 34-35 are held in the position to which they have been moved, by the engagement of their ends against the flat sides of 30 the bay 33 in which they work. The ratchet plate 41 is now in position to again impart a like motion to the spring contacts upon the succeeding actuation of the pull chain 45.

35 Various modifications in detail and arrangement of the parts will readily occur to those skilled in the art without departing from what I claim as my invention.

I claim:

1. In an electric lamp socket, a body comprising a pair of insulating buttons recessed on their adjacent faces to afford a substantially closed switch chamber, switch terminals comprising a pair of exterior straps carried by one of said buttons and angled 45 into the switch chamber on opposite sides thereof, said straps piercing the other button of said body, together with a switch contact coöperating with said terminals and mechanism within said chamber for imparting 50 an intermittent motion to said switch

contact, and a binding screw on the exterior portion of one of said straps.

2. In an electric lamp socket, an insulating body comprising a pair of insulating buttons recessed on their adjacent faces to afford a substantially closed switch chamber having a rectangular bay at one end thereof, an exterior wire terminal strap having an arm angled into said rectangular bay to form a switch terminal, a lamp engaging terminal at one end of the insulating body, a strap extending therefrom exterior to the insulating body but having an end angled into said rectangular switch chamber, in combination with a rotary switch piece 60 working in said rectangular bay and serving to make and break electrical connection between said switch terminals, together with a ratchet operated mechanism for rotating said switch contact.

3. In an electric lamp socket, an insulating body comprising a pair of insulating buttons recessed on their adjacent faces to afford a substantially closed switch chamber having a rectangular bay at one end thereof, a rotary switch member arranged substantially centrally in said bay and journaled in one of said buttons, a stationary spindle bearing supported in the other of said insulating buttons and forming a trunnion on which said rotary switch member is journaled, switch operating mechanism mounted on said stationary spindle, a wire terminal strap exterior to said insulating body and having an arm angled into said 80 rectangular bay and lying against one side thereof to form a switch terminal, a lamp engaging terminal at one end of the insulating body, a strap extending therefrom exterior to the insulating body and having a 90 terminal angled into said rectangular switch chamber and lying against the wall thereof opposite the binding screw terminal, together with means for operating the switch mechanism to impart intermittent rotary 95 movement to the switch member rotating in the bay.

In testimony whereof I have signed my name to this specification.

FREDERIC P. GATES.
